R. E. KELM

HUMIDIFIER FOR HOT AIR FURNACES

Filed March 21, 1922

Richard E. Kelm
Inventor
By
C. Storrey, Esq.

UNITED STATES PATENT OFFICE.

RICHARD E. KELM, OF MILWAUKEE, WISCONSIN.

HUMIDIFIER FOR HOT-AIR FURNACES.

Application filed March 21, 1922. Serial No. 545,406.

To all whom it may concern:

Be it known that I, RICHARD E. KELM, a citizen of the United States, and resident of Milwaukee, in the county of Milwaukee and State of Wisconsin, have invented certain new and useful Improvements in Humidifiers for Hot-Air Furnaces; and I do hereby declare that the following is a full, clear, and exact description thereof.

10 My invention relates to a humidifier of new and improved construction, which is particularly adapted for use in connection with hot air furnaces.

It is a well known physical fact that the 15 cold air, which is drawn into the chamber surrounding the furnace and heated thereby for the purpose of conveying heat to the rooms of the house, loses thereby a large percentage of its relative humidity. In order 20 to promote the health of the occupants of the house, therefore, as well as to prevent the woodwork and furniture from becoming excessively dry, it is generally customary to provide a pan, or similar receptacle, which 25 is within the air chamber and from time to time is filled with water for the purpose of supplying the desired moisture.

The primary object of the present invention is to provide a device of this general 30 nature, which will be so constructed and located that the vapor rising therefrom may be uniformly mingled with the air as it passes through the heating chamber.

It is, also, an object of the invention to 35 provide a more practical and convenient means, whereby the water may be always maintained within the furnace without any particular attention on the part of the operator.

40 The invention consists further in certain structural details and combinations thereof, which will be more particularly described in connection with the accompanying drawing and subsequently claimed.

45 In the drawing, the figure represents a vertical sectional view through a hot air furnace with my invention applied thereto.

Referring more particularly to the drawing, the numeral 5 indicates a fire pot and 50 the ash-pit of a furnace of conventional design. The bottom 7 of the ash-pit upon which the furnace is supported, is preferably provided with an annular groove 8 within which the rim of the ash-pit 6 is set. 55 Outside of this groove is a downwardly extending channel or trough 9, which is

formed integral with the bottom 7 and supports, the latter in spaced relation to the floor. The outer flange of the trough 9 supports a cylindrical housing 10, which substantially surrounds the furnace and provides a space into which the cold air is drawn through an opening 11, which is located near the trough 9. The air passing upwardly around the furnace and around 60 openings in the heating drum 12 becomes heated and passes upwardly through pipes which are connected at 13. The trough 9 is adapted to be partly filled with water and being closely connected with the furnace 65 causes the water to become moderately warm and the vapor rising therefrom, becomes thoroughly mingled with the air which is drawn in through the inlet 11. The trough 9 is, also, preferably provided with a supply pipe 14 which is controlled by a stop cock 15 and with a valve 16, which is automatically actuated by a float 17 to maintain the water in the trough at a constant level.

70 In addition to the advantages mentioned above, it will be, also, apparent that the location and construction of the water receptacles, as set forth, not only makes it convenient to supply the water automatically, but also permits use of a larger quantity 75 of water than constructions hitherto used with its resultant beneficial results.

The water, also, absorbs and conserves the 80 heat which, in the usual construction, is radiated toward the ground and lost. The water, also, acts as a dust collector and renders the air, which is carried into the pipes, clean and wholesome and consequently, to a great extent, prevents the accumulation 85 of dust and dirt in the house.

90 It will, also, be understood, that while I have shown and described specifically a way in which the invention may be carried out, various changes in the shape, relative sizes of the parts, and the like, may be made 95 without departing from the spirit of the invention.

I claim:—

1. A hot air furnace comprising a fire pot, an ash pit, a base having an annular water trough surrounding said ash pit and having inner and outer concentric walls, said ash pit having an elevated floor joining the inner walls of said water trough to form a dead air space under the ash pit only, and an outer casing supported from the outer wall of said water trough and having a cold

air inlet in close proximity to said water trough.

2. The combination of a trough containing water, a cylindrical housing carried by the outer wall of the trough, a fire pot, an ash pit, a bottom for said ash pit carried by the upper part of the inner wall of said trough, said bottom having dead air space

below to prevent the absorption of heat beneath said ash pit.

In testimony that I claim the foregoing I have hereunto set my hand at Milwaukee, in the county of Milwaukee and State of Wisconsin.

RICHARD E. KELM.
